UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC-LAMP SOCKET.

1,272,146.

Specification of Letters Patent.

Patented July 9, 1918.

Application filed February 8, 1913. Serial No. 747,098.

To all whom it may concern:

Be it known that I, GEORGE B. THOMAS, a citizen of the United States of America, and residing at Bridgeport, in the county of Fairfield and State of Connecticut, have invented a certain new and useful Improvement in Electric-Lamp Sockets, of which the following is a specification.

My invention relates to electric lamp sockets and particularly to pull sockets, the object of my invention being to provide an indicating device by means of which the position of the socket switch may be readily ascertained.

15 In the accompanying drawing,

Figure 1 is a side elevation of a pull socket showing my indicator in one form;

Fig. 2 is a side elevation of the socket with its inclosing casing removed;

20 Figs. 3 and 4 are plan of side elevation of the indicator;

Fig. 5 is a side elevation of the chain rail;

Fig. 6 is a detached perspective of the indicator mechanism parts;

Fig. 7 is a rear and side elevation of the indicator disk;

Fig. 8 is a side elevation showing the rail in position to operate the indicator mechanism; and

Fig. 9 is a side elevation of a modification, and Fig. 10 is a side elevation partially in section showing the switch mechanism;

35 It is sometimes of service to have on a lamp socket an indicator to disclose the position of the socket switch. This is of little importance when a lamp is placed in the socket, but when the socket is used as 40 a plug receptacle and the current thus tapped to another point, it becomes a matter of convenience and sometimes of importance to know the position of the socket switch.

45 I have applied my invention in the example shown, to a pull socket. As illustrated in Fig. 1, the socket casing comprises the usual cap 10 and shell 11. In the latter a sight aperture 12 of convenient size is cut 50 through which is disclosed a segment 13 of the indicator disk 14. This disk is fast on a spindle 15 journaled in perforated lug 16 on the spacing bar 17 which carries the detachable chain bell 18 in the manner de-

scribed in the Hubbell Patent No. 943,077. 55 Also fast on the spindle 15 is mounted a ratchet 19, the teeth of which lie in the path of the finger 20 on the chain rail 21 as the latter travels back to actuating position under the influence of its return spring 22. On each full actuation of the chain and consequently each change of position of the switch, the indicator disk is thus advanced a quarter revolution, there being four teeth to the ratchet 19. 65

In order to prevent the rotation of the indicator disk in the wrong direction, as the finger 20 of the chain rail on the outward travel of the chain, rides over the back of the teeth on the actuating ratchet 19, I 70 provide the disk 14 with a series of teeth formed for example on the back of a plate 23 which is soldered to one face of the indicating disk. Against this plate a detent 24 is pressed by means of a spring 25. This 75 detent is here shown as a strap 24 having a head 26 through which freely passes the spindle 15 and in the periphery of which apertures 27 are cut to receive the teeth and the plate 23. The opposite end of the strap 80 is offset at 28 and passed through the aperture 29 in the standard which thus holds the detent against rotation.

Obviously the teeth on the ratchet 19 may be faced in the opposite direction, as illustrated at 30 in Fig. 9, and the actuating lug 31 on the chain rail oppositely beveled so that it rides over the ratchet lug 30 on its return movement under the influence of the return spring 22. In this instance the indicator disk is actuated by the positive pull 85 of the chain and the return spring is thus relieved of the additional burden otherwise imposed upon it, of actuating the indicator disk. 90

The current is led to one branch of the socket through the switch in the general manner illustrated in the Hubbell Patent 565,541. One wire is connected to terminal 32 which is in electrical contact with the 100 screw shell 33. The other wire is connected to terminal 34, from the base of which extends the switch terminal 35 overlying one of the teeth 36 on the lower button 37 of the switch body. The circuit to the center contact (not shown) of the socket is established through the switch piece 38 which has wings 105 riding the teeth 36 and is provided with a

series of ratchet notches 39 in which engage the pawl teeth 40 struck down from the plate 41 carried on the lower face of the insulating disk 42. An outwardly extended 5 arm on the latter carries the chain rail 21 with its tongue 20 by means of which the indicator 14 is operated on each successive movement of the switch piece 38, as will be readily understood from the explanation

10 above given.

Various other arrangements to accomplish the same end will readily suggest themselves, and I do not limit myself to the details of construction shown.

15 I claim as my invention:—

1. An electric lamp socket having line and lamp terminals and a switch mechanism interposed between the same, together with an indicator for disclosing the position of 20 the switch and means for securing an intermittent engagement between the switch mechanism and indicator for actuating the latter.

2. An electric lamp socket having line and 25 lamp terminals, an interposed switch mechanism, an apertured inclosing casing, an indicator showing the position of the switch and visible through the aperture in the casing, and an operative connection between 30 said indicator and switch mechanism.

3. An electric lamp socket having line and lamp terminals, an inclosing casing, a switch mechanism within the latter and operating means therefor extending through the casing, an indicator mounted independent of 35 the switch mechanism and an operative connection between the switch operating means and the indicator for actuating the indicator to show the position of the switch.

40 4. An electric switch comprising a rotary switch piece, an indicator rotating on an independent axis and serving to show the position of the switch, operating mechanism for the switch piece and an operative connection between the indicator and said switch mechanism.

5. An electric switch comprising a rotary switch piece, an indicator rotating on an independent axis at an angle to the axis of the 50 switch piece and serving to show the on or off position of the switch, operating mechanism for the switch piece and an operative connection between the indicator and said switch mechanism.

55 6. An electric switch comprising a rotary switch piece, an oscillating member having a separative connection therewith for rotating the same, an indicator serving to show the on or off position of the switch piece, 60 and intermittent independent operative con-

nnection between the oscillating member and indicator, for the purpose described.

7. An electric lamp socket comprising a socket body, an inclosing cap and apertured shell casing therefor, an indicator within 65 said casing but visible through the apertured shell, a switch on the socket body and means operatively connected therewith for actuating said indicator.

8. An electric lamp socket comprising a 70 socket body, a switch carried thereby, an inclosing casing comprising a cap and apertured shell and a switch indicator visible through the aperture in said shell.

9. An electric switch comprising a switch 75 piece, an operating device therefor having a pawl and ratchet actuating connection between said parts, an indicator serving to show the on or off position of the switch and an independent pawl and ratchet mechanism 80 for operating said indicator on the actuation of the switch piece.

10. In an electric switch, a switch operating mechanism, an indicator mounted on an independent axis serving to show the on or 85 off position of the switch, and a pawl and ratchet connection between the switch operating mechanism and the indicator.

11. In an electric switch, a switch mechanism having an oscillating member, an indicator mounted on an independent axis for showing the position of the switch and a pawl and ratchet connection between said oscillating member and indicator for actuating the latter on the actuation of the 95 switch.

12. In a rotary switch, the combination of an insulating base, switch mechanism mounted thereon and including a relatively rotatable switch member, an oscillating switch 100 operating lever, pawl and ratchet connection between said lever and the rotatable switch member whereby the switch member will be rotated with a step by step movement as the switch lever is oscillated, a rotatably supported switch indicator, and pawl and ratchet connection between the switch lever and said indicator whereby as the lever is oscillated the indicator will be rotated with 105 a step by step movement corresponding to the movement of the rotatable switch member.

In testimony whereof I have signed my name to this specification in the presence of two subscribing witnesses.

GEORGE B. THOMAS.
